UNITED STATES PATENT OFFICE.

HENRY C. THOMSON, OF WEST ROXBURY, MASSACHUSETTS.

FILE WRAPPER.

Application filed August 4, 1922. Serial No. 579,761.

To all whom it may concern:

Be it known that I, HENRY C. THOMSON, a citizen of the United States of America, residing at West Roxbury, in the county of 5 Suffolk and State of Massachusetts, have invented new and useful Improvements in File Wrappers, of which the following is a specification.

This invention relates to file wrappers or jackets for use in professional and business offices and where all papers and data relating to a given subject are kept collected in a single flat wrapper or jacket for convenient reference, and where, in many instances, data 10 is recorded upon the face of the wrapper, and also where the subject matter therein is of such a nature as to require the person in charge of said file to record upon the wrapper, acts relative to the subject matter 15 and the dates thereof. In such latter requirements it has heretofore been customary to record the data on the outside of the wrapper. In some instances the face of the wrapper has been printed with spaces left 20 blank to record the distinctive name of the subject matter therein, or the name of the person in whose favor the file is created and also spaces for recording data with respect 25 of an act which has been or is to be performed. When a considerable number of 30 such files are assembled in massed relation, as in a file drawer, in order to become cognizant of the nature of the data recorded on the face of the file, it has been necessary to 35 remove the file from its position in the file drawer to observe same. The object of the present invention is to provide a flat file 40 wrapper preferably with folding flaps that may be designed similar to those heretofore 45 generally in use, but constructed and arranged to present a permanently doubled and folded-down edge portion extending along one side of the wrapper and adapted 50 to receive identification clips or like devices, said devices to act as identifying means 55 with respect to data contained within the file whereby said devices will, without removing the file from its assembled relation with respect of its neighbor in the file drawer, disclose to the person consulting the file certain predetermined data. For example in 60 the case of an application for Letters Patent, a blue signal secured upon the folded down edge may be used to disclose to the observer, 65 without his handling the file, the fact that the application papers have been sent to the

inventor for execution, and a red signal to indicate that the case has been returned by the inventor while a numbered signal may be utilized to fix the date of certain past or 60 future procedures.

Various forms of clips intended to be secured to the edge of file wrappers or jackets have been devised to bear indicating indicia, but these have heretofore been nearly useless and subject to the objection that they are constantly being pried off and lost on the bending back of the file along the edge when the clips are applied as required to open 65 the wrapper. The foregoing and other objects and advantages of the invention will more fully appear from the following detailed description taken in connection with the accompanying drawings, and the distinctive features of novelty will be pointed 70 out in the appended claims.

Referring to the drawings:

Fig. 1 is a front elevation of a file wrapper embodying the invention;

Fig. 2 is an end view thereof with the 80 flaps folded down;

Fig. 3 is a rear view;

Fig. 4 is an end view showing the flaps partly open, and

Fig. 5 is an end view showing the flaps 85 fully opened.

The wrapper or jacket of my invention may be produced of any suitable material such as stout and fairly stiff paper, either plain or suitably reinforced as desired. The 90 wrapper comprises a front or body portion 10 of a length corresponding to the length desired for the wrapper, and of a width corresponding to the desired width of the 95 wrapper plus a small addition to provide for the permanently doubled and folded down edge portion of my invention as now to be explained. Flaps 11, 12, and 13 extend from the sides, and from one or both 100 ends of the body portion to be folded inward to constitute the back of the wrapper in accordance with usual practice, there being only one end flap 13 shown in the present embodiment, although this is merely illustrative, and so far as the invention is concerned the wrapper may be produced without 105 any end flaps at all.

In accordance with my invention the material of the wrapper is permanently 110 doubled and folded down upon itself inward for a small distance along one edge portion of the body 10, this doubled down

portion being indicated at 14. This folded-down portion may be glued or otherwise cemented or secured to the body 10 so that it presents a permanent, stiffened edge extending the length of the wrapper at one side thereof adapted to receive one or more clips 15 that may serve as, or bear any suitable identification indicia. One of the side flap, i. e. as shown the flap 12, extends from this folded-down edge portion with the line of flexing of this flap at the inner edge of this bent-down portion as indicated at 16. Hence the bending of this flap 12 in nowise interferes with the mounting of the clips 15 on the edge portion 14, and the wrapper may thus be opened and manipulated as required without any tendency to dislodge the clips 15. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters 30 Patent is:

1. A file wrapper or jacket, comprising a body portion with folding flaps borne thereby, and with a relatively stiffened and reinforced edge along one side thereof, pro-

duced by a permanently doubled and adhesively secured portion folded down along said side, from the inner edge of which folded-down portion one of said flaps extends and is predisposed for bending. 35

2. A one-piece file wrapper or jacket, comprising a body portion with folding flaps extending therefrom, and with a relatively stiffened and reinforced edge at one side thereof produced by a permanently doubled and adhesively secured portion folded down 40 along said side, and with one of said flaps extending and predisposed for flexing from the inner side of said stiffened edge portion. 45

3. A one-piece file wrapper or jacket, comprising a body portion provided with a 50 folding flap, and with a stiffened edge along one side thereof, produced by a portion folded down and held permanently doubled, by adhesive, from the inner side of which said flap extends and is predisposed for 55 bending.

4. A one-piece file wrapper or jacket, comprising a body portion provided with a folding flap, and with a stiffened edge along one side thereof, produced by a permanently 60 doubled, folded down and adhesively secured portion, from the inner side of which said flap extends and is predisposed for bending, and a member adapted to bear identification indicia or the like secured to 65 said stiffened edge.

In testimony whereof I affix my signature.

HENRY C. THOMSON.
